United States Patent Office.

ELIJAH LINDSLEY, OF NEENAH, WISCONSIN.

Letters Patent No. 80,639, dated August 4, 1868.

IMPROVEMENT IN HINGES.

The Schedule referred to in these Letters Patent and making part of the same.

TO ALL WHOM IT MAY CONCERN:

Be it known that I, ELIJAH LINDSLEY, of Neenah, Winnebago county, and State of Wisconsin, have invented a new and useful Improvement in Right and Left-Handed Loose-Jointed Butts or Hinge; and I do declare that the following is a full, clear, and exact description of the construction and operation of the same, reference being had to the annexed drawings, making a part of this specification, in which—

Figure 1 is a perspective view.

Figure 2 is a sectional view of one plate.

Figure 3 is a perspective view of pivot-pin.

Figure 4 is a sectional view of the other plate.

Figure 5 is a back view, when closed.

Figure 6 is an end view closed.

a is the shoulder, which encircles the pivot-pin *b b*, in the centre, and bearings upon which the plates *d d* rest, and turn thereby, forming an eccentric, which adjusts itself to place whenever the butt or hinge is opened or closed either way, as seen at *a* in fig. 1.

b b is the pivot-pin, (encircled in the centre by shoulder *a*), with two short bends near the shoulder, one to the right and the other to the left, thereby bringing both ends of the pin on parallel lines, and forming pivots for thimbles or sockets *c c* to play upon, as seen in fig. 1.

c c are the thimbles or sockets, as seen in figs. 2 and 4, and play around pivot-pin *b b*, as seen in figs. 1 and 5, thereby forming a perfect butt or hinge, which may be opened or closed either way without raising the plate or pin.

d d are the plates, with thimbles or sockets, on parallel line with centre of plate, both being constructed alike, as seen at *c c* in figs. 2 and 4.

Taken all in combination, it forms a simple, durable, and cheap right and left-hand butt or hinge, without changing, reversing, or taking apart in any way.

What I claim as my invention is—

The bent pivot *b*, in combination with shoulder *a* and plates *d d*, the whole forming a right and left-hand hinge, substantially as herein shown and described.

ELIJAH LINDSLEY.
